GEORG WIENHOLTZ, OF ESSEN-ON-THE-RUHR, GERMANY, ASSIGNOR TO FRIED. KRUPP AKTIENGESELLSCHAFT, OF ESSEN-ON-THE-RUHR, GERMANY.

GUN-CARRIAGE.

1,079,815.

Specification of Letters Patent. Patented Nov. 25, 1913.

Application filed April 5, 1912. Serial No. 688,676.

To all whom it may concern:

Be it known that I, GEORG WIENHOLTZ, residing at Essen-on-the-Ruhr, Germany, a subject of the Emperor of Germany, have invented a certain new and useful Improvement in Gun-Carriages, of which the following is a specification.

The present invention relates to gun carriages that have a reversible cranked wheel axle, for the purpose of changing the firing height. In accordance with this invention, carriages of this kind are provided with a device, which adjusts itself when the axle is reversed and limits the movement of elevation for each firing height to such an extent, that the gun barrel can never be given so high an elevation that it will hit the ground during the recoil.

The accompanying drawings, representing one embodiment of the present invention show in Figure 1 a side view, partly in section, of the lowest firing height of the gun carriage with the gun barrel slightly elevated; Fig. 2 a part of Fig. 1 in larger scale; Fig. 3, a top, plan view of Fig. 1, with some of the details broken off; Fig. 4, a front view of Fig. 1, but with the gun barrel laid level; Fig. 5 a view corresponding to Fig. 1 but showing the mean firing height of the gun carriage with the gun barrel in mean elevation. Fig. 6 another side view corresponding to Fig. 1, but showing the greatest firing height of the gun carriage and with the gun barrel in highest elevation.

The gun barrel is guided on the slide carrier or cradle B, which includes the brake and counter recoil-device (not shown in the drawing). By means of horizontal trunnions b¹ the cradle B rests in bearings on the trail body D. An elevating gear, having a toothed arc C and a hand wheel P, is inserted between the cradle B and the trail body D. The elevating gear has for the sake of clearness been omitted in Figs. 2, 5 and 6.

The axle for the carriage wheels E is cranked, and consists of the cranked axle shanks G and the middle part G¹, which latter is mounted to turn in the trail body D. The bent back arms g² of the axle shanks G are flattened out to the semi-circular disks which possess each five holes g³, g⁴, g⁵, g⁶, and g⁷ (Figs. 1, 2, 5 and 6). Each pair of these holes may be brought to register with a pair of holes in the adjacent walls

of the trail body D, by corresponding adjustment of the wheel axle. As a consequence, the wheel axle may be secured in five different positions relative to the trail body, by the insertion of a key bolt H in one of the holes g³ to g⁷ and the hole in the trail side (see Figs. 1, 2 and 4 to 6); and the carriage may therefore be given five different firing heights.

The rear end of the cradle B carries two projecting arms N, which are intended to co-operate with two stepped disks R, secured on the middle part G¹ of the wheel axle. Each of these disks is provided with five working surfaces r¹, r², r³, r⁴ and r⁵ (see Figs. 1, 2, 5 and 6) for co-operation with a toe n¹ on the free end of the projecting arms N. The working surfaces r¹ to r⁵ are arranged in such a manner that in any one of the firing heights of the carriage, the movement of the projecting arm N, and subsequently of the gun barrel, is limited to such an extent by one of the working surfaces, that the gun barrel can never be given such an elevation, that it could hit the ground when recoiling.

If the gun has to be fired at only slight elevation, the carriage is given its lowest firing height, that is, the wheel axle is given such a position relative to the trail body, that the middle part G¹ thereof will be located perpendicularly underneath the axle shanks G (Figs. 1 to 4), securing the wheel axle rigidly to the trail body by inserting the key bolts H in the holes g³ of the arms g² of the axle shanks. The working surfaces r¹ of the stepped disk R will then be in the path of the projecting arms N, so that the gun barrel can only be elevated up to the position illustrated in Fig. 1, in which elevation the gun barrel will not reach the ground during the recoil. (See the position of the recoiled breech end indicated by dot and dash lines in Fig. 1.)

Should the gun barrel have to be given a mean elevation, that means, an elevation high enough to cause the breech of the gun to hit the ground in case the lowest firing height were retained then the key bolts H are removed, the wheel axle turned to the position indicated in Fig. 5, wherein the holes g⁶ of the axle shank-arms g², register with the holes in the trail sides, and lastly, the wheel axle locked to the trail body by means of the key bolts H. The middle part

G¹ of the wheel axle will then be on a level with the axle shanks G, which means that the gun carriage has been adjusted to its middle firing height. The working surfaces

5 r³ of the stepped disks R, lie then in the path of the projecting arm N, and as a consequence the gun barrel can be elevated to the position shown in Fig. 5 only and no higher.

When it is desired to give the gun barrel 10 its highest elevation, the carriage is set at its greatest firing height (Fig. 6), where the holes g⁷ of the arms g² of the axle shanks, register with the holes of the trail sides. The working surfaces r⁵ of the stepped disks 15 R nearest the axle part G are then located in the path of the projecting arms N.

Besides the three mentioned firing heights of the carriage there are two intermediate positions, wherein either the one or the 20 other of the holes g⁴ or g⁶ of the arms g² of the axle shanks register with the holes in the trail sides and one or the other of the working surfaces r² or r⁴, respectively lies in the path of the projecting arms N.

25 Should the gun barrel have the maximum elevation for each of the adjusted firing heights, as in the case for instance, in Figs. 5 and 6, a diminishing of the firing height can only be undertaken after the gun's elevation has been diminished; as otherwise after diminishing the firing height the breech end of the gun barrel will strike the ground before reaching the end of the recoil. The step surfaces r⁶, r⁷, r⁸ and r⁹ (Fig. 35 2) between the working surfaces r¹, r², r³, r⁴ and r⁵ of the stepped disks R, have been provided to prevent any breach of this rule, as these surfaces together with the toes n¹ on the projecting arms N form stops when

40 touching. A reduction of the firing height is therefore only possible after the faces n² have been brought out of engagement with the faces r⁶, r⁷, r⁸, and r⁹ of the stepped disks R; this means, after the elevation of 45 the gun barrel has been diminished so much, that the breech end of the recoiling gun barrel will not strike the ground.

I claim:—

1. In a gun carriage having a rocking member partaking of the elevating movement of the gun barrel and a trail wherein said rocking member is mounted; the combination of a cranked wheel axle, the middle part of which is mounted to turn in said trail; a pair of flanges on said axle adjacent the trail sides; a plurality of bolt holes in said flanges; a bolt hole in each of said trail sides; a pair of key bolts adapted to lock said cranked axle to said trail to prevent its turning therein, by means of said bolt holes in the trail sides and either pair of said bolt holes in the flanges, for the purpose of giving the gun barrel different heights from the ground by using different 60 pairs of flange bolt holes, and members on

said trail and rocking member adapted to limit the maximum elevation of the gun barrel for each of said different heights.

2. In a gun carriage having a cradle for carrying the gun barrel and a trail in which the cradle is mounted to rock; the combination of a cranked wheel axle, the middle part of which is mounted to turn in said trail; a pair of flanges on said axle adjacent the trail sides; a plurality of bolt holes in said flanges; a bolt hole in each of said trail sides; a pair of key bolts adapted to lock said cranked axle to said trail to prevent its turning therein, by means of said bolt holes in the trail sides and either pair of said bolt holes in the flanges, for the purpose of giving the gun barrel different heights from the ground by using different pairs of flange bolt holes and members on said trail and cradle adapted to limit the maximum elevation of the gun barrel for each of said different heights.

3. In a gun carriage having a rocking member partaking of the elevating movement of the gun barrel, a trail wherein said rocking member is mounted, and an independent elevating gear for elevating said rocking member with the gun barrel relative to said trail; the combination of a cranked wheel axle constructed to give a plurality of fixed firing heights to the gun barrel; radial disks on the middle part of said wheel axle; arms projecting downward from said rocking member and adapted to coöperate with said radial disks to limit the maximum elevation of the gun barrel for each of said fixed firing heights.

4. In a gun carriage having a cradle with the gun barrel slidably mounted thereon, a trail in which the cradle is mounted to rock, and an independent elevating gear for elevating said cradle with the gun barrel relative to said trail; the combination of a cranked wheel axle constructed to give a plurality of fixed firing heights to the gun barrel; radial disks on the middle part of said wheel axle; arms projecting downward from said cradle and adapted to coöperate with said radial disks to limit the maximum elevation of the gun barrel for each of said fixed firing heights.

5. In a gun carriage having a cradle with the gun barrel slidably mounted thereon, a trail in which the cradle is mounted to rock, and an independent elevating gear for elevating said cradle with the gun barrel relative to said trail; the combination of a cranked wheel axle constructed to give a plurality of fixed firing heights to the gun barrel; radial disks on the middle part of said wheel axle; each of said radial disks being composed of a plurality of circle sectors of different radii; arms projecting downward from said cradle and adapted to coöperate with said radial disks to limit the maximum

elevation of the gun barrel for each of said fixed firing heights.

6. In a gun carriage having the cradle with the gun barrel slidably mounted thereon; a trail in which the cradle is mounted to rock, and an independent elevating gear for elevating said cradle with the gun barrel relative to said trail; the combination of a cranked wheel axle constructed to give a plurality of fixed heights to the gun barrel, a plurality of circle sectors of different radii, forming stepped radial disks on the middle part of said wheel axle with the number of steps equal to the number of firing heights of the gun barrel; arms projecting downward from said cradle and adapted to operate with said radial disks to limit the maximum elevation of the gun barrel for each of said fixed firing heights.

20 7. In a gun carriage having a cradle with the gun barrel slidably mounted thereon; a trail in which the cradle is mounted to rock and an independent elevating gear for elevating said cradle with the gun barrel relative to said trail; the combination of a cranked wheel axle constructed to give a plurality of fixed firing heights to the gun barrel, a plurality of circle sectors of different radii forming stepped radial disks on the middle part of said wheel axle with the number of steps equal to the number of firing heights of the gun barrel; arms projecting downward from said cradle and adapted to coöperate with said radial disks to limit the maximum elevation of the gun barrel for each of said fixed firing heights; the circle sector of the longest radius intended for the lowest firing height, and that of the next longest radius intended for the next lowest firing height, whereby the maximum gun barrel elevation for each firing height is greater than the maximum gun barrel elevation of the next lower firing height.

8. In a gun carriage having a cradle with the gun barrel slidably mounted thereon; a trail in which the cradle is mounted to rock, and an independent elevating gear for elevating said cradle with the gun barrel relative to said trail; the combination of a cranked wheel axle constructed to give a plurality of fixed firing heights to the gun barrel, a plurality of circle sectors of different radii, forming stepped radial disks on the middle part of said wheel axle with the number of steps equal to the number of firing heights of the gun barrel; arms projecting downward from said cradle and adapted to coöperate with said radial disks to limit the maximum elevation of the gun barrel for each of said fixed firing heights, a shoulder on each of said arms engaging the respective radial surfaces of said steps at the respective maximum gun barrel elevations, whereby any change of firing height from a greater to a smaller will be prevented until after the lowering of the elevation of the gun barrel.

9. In a gun carriage having a rocking member partaking of the elevation movement of the gun barrel, a trail wherein said rocking member is mounted, a cranked wheel axle, the middle part of which is mounted to turn in said trail, means for locking said axle and trail together for different firing heights of the gun barrel and abutments on said axle and rocking member adapted to limit the maximum elevation of the gun barrel for each of said different firing heights.

The foregoing specification signed at Bar- 80
men, Germany, this 15th. day of March, 1912.
